UNITED STATES PATENT OFFICE

107,664

DESIGN FOR A BEDSPREAD OR SIMILAR ARTICLE

Joseph Shurin, Roxbury, Mass.

Application September 11, 1936, Serial No. 64,818

Term of patent 3½ years

To all whom it may concern:

Be it known that I, Joseph Shurin, a citizen of the United States, residing at 25 Castlegate Road, Roxbury, Massachusetts, have invented a new, original, and ornamental Design, for Bedspreads or Similar Article, of which the following is a specification, reference being had to the accompanying drawing, in which:—

The figure is a perspective view of a bedspread showing my new design.

I claim:

The ornamental design for a bedspread or similar article as shown.

JOSEPH SHURIN.
